COMBINED IGNITION COIL ATTACHMENT AND COIL WIRE SUPPORTING CONNECTOR

Russell G. Livingston, Los Angeles, Calif., assignor to
Hallett Manufacturing Company, Los Angeles, Calif.,
a corporation of California

Filed Apr. 24, 1964, Ser. No. 79,677

Term of patent 14 years

(Cl. D77—1)

FIG. 1.

FIG. 2.

FIG. 3.

FIG. 4.

FIG. 1 is a perspective view of a combined ignition coil attachment and coil wire supporting connector showing my new design;

FIG. 2 is a bottom plan thereof;

FIG. 3 is a rear elevation thereof; and

FIG. 4 is a side elevation thereof.

The dominant features of my design reside in those portions shown in full lines.

I claim:

The ornamental design for a combined ignition coil attachment and coil wire supporting connector, substantially as shown and described.
